UNITED STATES PATENT OFFICE.

EMILE FRANCKAERTS, OF SAN FRANCISCO, CALIFORNIA.

DOOR-HOLDER.

1,157,376.

Specification of Letters Patent.

Patented Oct. 19, 1915.

Application filed July 9, 1915. Serial No. 38,869.

To all whom it may concern:

Be it known that I, EMILE FRANCKAERTS, a citizen of the United States, and a resident of San Francisco, in the county of San Francisco and State of California, have made an Improvement in Door-Holders, of which the following is a specification.

My present invention is an improvement upon the door-holder, for which I have received Letters Patent No. 1100475, dated June 16, 1914. In that case the holder could be used only on the outside of the door, but, by the means I have effected, which are very simple in character, the shoe or stop member proper is reversible, and the holder is adapted for use on either the inside or the outside of the door. When used on the inside, the stop member being reversed, the door-holder proper is supported upon a skeleton base which spaces it from the door, so that the stop member will not come in contact therewith.

The details of construction, arrangement, and operation are as hereinafter described, and illustrated in the accompanying drawing, in which:

Figure 1 is a perspective view of the complete invention applied to a door, a portion being broken out to show an interior arrangement. Fig. 2 is a vertical longitudinal section of the complete door-holder, including the skeleton base. Fig. 3 is a perspective view of the skeleton base or back plate constituting a support for the door-holder proper. Fig. 4 is a longitudinal section of the lower portion of the door-holder, showing a reversible shoe or stop member arranged in the manner required when the door-holder as a whole is applied to the outside of the door.

In the drawing, A indicates the main or outer casing of the door-holder, B the smaller or auxiliary casing, which is slidable in the other, C the shoe or stop member, and D the skeleton base support for the door-holder proper. These parts are formed of metal. The shoe C has a tapered shank which is pivoted to, and extends into, the lower end of the inner, slidable casing B. The said shoe or stop member has a rubber block, secured in a dove-tailed socket by a transverse screw.

A rod 1 extends from the flanged head of the inner casing B down through plates or transverse partitions 2-3 which are fixed in the main casing A. A spiral spring 4

encircles the rod above the partition 2, and a shorter spring 5 encircles the rod above the lower partition 3. Between said partitions is arranged a locking member and trip 6, which consists of a plate pivoted in the back of the fixed casing A, and projecting through a slot in the front of the same. This plate is provided with an aperture of the required dimension to enable it to engage the rod 1 by friction and lock it so as to hold the stop member projected downward to the required extent. By pressing downward upon the projecting end of the plate 6, the lower spring 5 is compressed and the rod 1 will slide upward through such locking member 6 and carry with it the inner casing B, together with the shoe C.

For any further details that may be deemed desirable in reference to the locking and trip mechanism, reference may be made to the description and drawing of my patent above referred to.

In the original there was no adaptation for reversal of the shoe or stop member, and therefore, the door-holder could only be used on the outside of a door, the spiral spring 7 (see Fig. 4) being in that case arranged on the left of the shank of the shoe C so as to throw the rubber block inward toward the door. As shown in said Fig. 4, the ends of the spring 7 are held in a socket 9 in the slidable casing B, and in a corresponding socket in the shank of the shoe C. For securing it to the shank a screw 8 is preferably employed, it being arranged as shown in Fig. 4. In the opposite side of the slidable casing B is another socket 9^a, and when it is desired to use the door-holder on the inside of the door, it is reversed from the position shown in Fig. 4 to that shown in Figs. 1 and 2, and in such case the outer end of the spring 7 enters the socket 9^a, as will be readily understood. When the door-holder is thus reversed from the position in Fig. 4 to that in Figs. 1 and 2, it is necessary to employ the skeleton base D in order to space the metal portion of the shoe C from the door. As shown in Fig. 3, the base B is provided with three screw-holes, to receive screws by which it and the door-holder proper are secured one upon the other and to the face of a door.

By the adaptation of the shoe for reversal, as described, and by the provision of a skeleton base support, the door-holder may be used on either outside or inside of a door,

as occasion requires, which is often a matter of convenience and much importance.

I claim:—

1. The improved reversible door-holder comprising a main casing adapted to be fixed in position, a spring-actuated smaller casing adapted to slide in said main casing, means for locking and tripping the inner casing, a shoe or stop member pivoted in the lower end of the inner casing and its shank projecting upward into the latter, a spring secured to said shank, the inner casing having at diametrically opposite points sockets for receiving the free end of said spring, whereby the shoe is adapted for reversal, as described.
2. The improved reversible door-holder

Copies of this patent may be obtained for five cents each, by addressing the "Commissioner of Patents, Washington, D. C."

comprising a main casing, a slidable spring-actuated inner casing, means for locking and tripping the latter, a reversible shoe or stop member pivoted in the lower end of the casing and its shank provided with a spring attachment adapted for engagement with either side of the inner casing, and a skeleton base upon which the door-holder proper is secured, said base serving to space the shoe or stop member from the door to which the attachment is applied in the manner described.

EMILE FRANCKAERTS.
